UNITED STATES PATENT OFFICE

2,538,605

SPEED AND BAROMETRIC RESPONSIVE
FUEL CONTROL FOR GAS TURBINESStanley M. Udale, Detroit, Mich., assignor to
George M. Holley and Earl Holley

Application March 12, 1945, Serial No. 582,266

3 Claims. (Cl. 60—41)

1

The object of this invention is to control the fuel supply of an engine by the density of the air and the speed of the engine. If such a device is installed on an airplane engine and if the airplane is dived, the increase in air density during the dive causes the engine to overspeed, and it is desirable therefore to restrict the fuel supply temporarily during the acceleration period and to allow the fuel supply to gradually increase to the desired amount after the plane has leveled off and the dive is over.

The figure shows diagrammatically the essential elements of my invention.

In the figure, 10 is the fuel entrance, 11 is the fuel exit to the engine, not shown, 12 is an engine-driven pump, which delivers each revolution an amount determined by the position of the control lever 13, 14 is a lever connected at one end to a liquid pressure responsive servomotor piston 15 and at the other end to the engine speed responsive piston 16.

An altitude or barometric element 17 moves the servomotor valve 18. An engine-driven pump 19 circulates lubricating oil past a temperature responsive heating element 20. When viscosity is high and temperature low, element 20 operates so that the effect of viscosity is negligible because of the electric heat available when the temperature is low.

The oil under pressure from pump 19 is conveyed through a passage 40 to cylinder 22 above speed responsive piston 16. An opening 23 in piston 16 allows oil to flow past a needle 25 in outlet 24. The needle 25 is controlled by lever 26, which is moved by the servomotor piston 15. An inlet 27 into cylinder 28 above the piston 15 leads from the oil pressure passage 21 into cylinder 28. A passage 29 admits oil under pressure beneath the piston 15 from the passage 21.

An outlet passage 30 delivers the oil back to the reservoir 42 from the central recess portion of the piston 15 and also delivers the oil flowing past the needle valve 25 from the cylinder 22, which flows through the opening 23 and past the piston 16.

The pressure generated by the pump 19 is determined by the the restriction 33. The oil under pressure in chamber 22 compresses a spring 31, which supports piston 16. A stop 32 limits the upward travel of the piston 16.

Operation

Assume that the plane driven by the gas turbine is in a dive, then the elements 17 will be compressed by the increase in atmospheric pres-

2

sure. Then the valve 18 will descend, and oil will escape through 29 from below the piston 15 past the valve 18 and then through passage 30 back to the reservoir 42. The pressure in chamber 22 therefore falls and the spring 31 raises the piston 16 to stop 32. Hence, one end of the lever 14 rises and fuel discharge from pump 12 is decreased. However, simultaneously the piston 15 descends and the other end of lever 14 descends, which moves the lever 13 down so as to increase the discharge from the pump 12 and thus the effect of the piston 16 rising is cancelled out so that actually lever 13 does not move very much during a dive.

15 When acceleration is over and when equilibrium is reached, the valve 18 assumes the neutral position in which it is shown because the piston 15 descends as far as the valve 18 descends. Then the escape of oil through piston 15 ceases. 20 The pressure in 22 then increases and the piston 16 leaves the stop 32 until the pressure of spring 31 plus pressure below piston 16 equals the pressure above the piston 16. The position of the valve 25 determines the pressure below the piston 16. Meanwhile the valve 25 has been opened somewhat by the descent of the piston 15; hence, the flow through orifice 23 has increased and the pressure drop through orifice 23 has increased so that the piston 16 descends. Hence, the effect of speed is more pronounced at sea level than it is at altitude. Hence, at sea level and at high speed, the speed effect of pump 19 assists the barometric device 17 in increasing the rate of discharge per revolution of the pump 12 to a maximum at maximum speed.

This device is particularly adapted to control the fuel supply to a gas turbine in which the turbine drives the oil pump 19 and the fuel pump 12 at speed proportional to the speed of the turbine. Gas turbines are particularly susceptible to excessive speeds.

At low speeds, the pressure generated by pump 19 is so low because of the comparatively large size of the restriction 33 that the spring 31 presses the piston 16 against the stop 32; hence, at low speeds the barometric element 17 is the only control for the lever 13.

The fuel outlet 11 is shown entering the combustion chamber 41 of a gas turbine 50. The 50 drive shaft 47 of the gas turbine is shown driving a bevel gear 43, which drives a gear connected to a shaft 45 which drives a variable stroke pump 46, of any well known type, in which there may be reciprocating pistons which engage with an 55 inclined plate 48. The position of this plate 48

may be moved by the pump control lever 13 to vary the pump discharge in a well known manner. A similar gear and shaft 44, also driven by the shaft 47, drives the oil pump 19.

What I claim is:

1. In a speed density fuel supply, an engine speed responsive oil pump, a servomotor piston connected to said oil pump, a barometric responsive means, a servomotor valve connected thereto and adapted to control said servomotor piston, an engine speed responsive piston, a cylinder therefor, a passage leading from said cylinder and connected to said engine speed responsive oil pump, a spring supporting said speed responsive piston and opposing the pressure generated by said pump, a fuel supply pump of the positive displacement type, a control lever therefor, a link, one end connected to the servomotor piston, the other end to the other piston, means connecting said control lever to said link whereby the control lever is moved both by the servomotor piston in response to liquid pressure changes and by the other piston in response to changes in engine speed.

2. A device as set forth in claim 1 in which there is a restricted opening from one side of the speed responsive piston to the other, to modify the pressure on the said latter piston, a return passage from the low pressure side of said latter piston to the inlet side of the speed responsive

oil pump, a second restriction in said passage, a valve controlling said second restriction, pressure responsive means connected to said last named valve, barometric responsive means controlling said pressure responsive means so that an increase in altitude closes said last named valve.

3. A device as set forth in claim 1 in which there is a restricted bypass in said cylinder around said speed responsive piston and a restricted outlet from the low pressure side of said cylinder and a valve therein, said last named valve being controlled by said barometric means whereby at high altitudes the valve is moved towards the closed position.
